UNITED STATES PATENT OFFICE.

HARRY LINCOLN TERRY, OF CHICAGO, ILLINOIS, ASSIGNOR TO FORHAN COMPANY, OF NEW YORK, N. Y., A CORPORATION OF NEW YORK.

DESIGN FOR A BOTTLE.

Application filed October 31, 1924. Serial No. 11,242. Term of patent 3½ years.

To all whom it may concern:

Be it known that I, HARRY LINCOLN TERRY, a citizen of the United States of America, residing in Chicago, county of Cook, State of Illinois, have invented a certain new, original, and ornamental Design for a Bottle, of which the following is a specification, reference being had to the accompanying drawings, forming part thereof, in which—

I claim:

The ornamental design for a bottle as shown.

HARRY LINCOLN TERRY.
